(57) **CLAIM**

The ornamental design for an electrical transportation tool, as shown and described.

DESCRIPTION

FIG. 1 is a top, front, right perspective view of an electrical transportation tool, showing my new design;

FIG. 2 is a bottom, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

Contrast in materials, unlimited by material or color, is shown using line shading on some surfaces.

The portions of the electrical transportation tool depicted in broken dashed lines form no part of the claimed design.
